UNITED STATES PATENT OFFICE.

CHARLES HARRIS JOHNSON, OF CHICAGO HEIGHTS, ILLINOIS, ASSIGNOR TO
THE JOHNSON, PARFITT TOOL COMPANY, OF SPRINGFIELD, ILLINOIS.

MOTIVE-FLUID-OPERATED HAMMER.

SPECIFICATION forming part of Letters Patent No. 666,757, dated January 29, 1901.

Application filed March 2, 1900. Serial No. 7,081. (No model.)

To all whom it may concern:

Be it known that I, CHARLES HARRIS JOHNSON, a citizen of the United States, residing at Chicago Heights, in the county of Cook, 5 State of Illinois, have invented certain new and useful Improvements in Motive-Fluid-Operated Hammers; and I hereby declare the following to be a full, clear, and exact description of the same, reference being had to the accompanying drawings, in which—

Figure 1 is a longitudinal central section of a pneumatic hammer embodying my invention; and Fig. 2 is a sectional view of part of the cylinder and the piston or hammer, 15 showing a modification in the arrangement of the supplemental supply or admission port of the piston.

Like symbols refer to like parts wherever they occur.

20 My invention relates generally to the construction of what are termed "valveless motive-fluid-operated tools," and especially to pneumatic hammers, and has for one of its objects a gradual admission of the motive fluid behind the piston or hammer during portions of its return and forward strokes, whereby greater power is obtained and recoil obviated. In carrying out this part of my invention I provide the piston with a supplemental inlet or admission port so arranged 25 as to admit motive fluid to the end of the piston before one-half of the return stroke of the piston is completed, and such a construction embraces one feature of my invention.

30 In order to obtain the best results, I have found that the supplemental admission-port should bear a relative proportion to the exhaust-ports of about one to six or one to four, and such a construction embodies a further 35 feature of my invention. There are other minor features of invention, all as will hereinafter more fully appear.

I will now proceed to describe my invention by reference to the drawings, so that others skilled in the art to which it appertains may 40 apply the same.

In the drawings, A indicates the handle, B the cylinder, and C the piston, of a pneumatic hammer. The handle A has the motive-fluid-50 supply passage a, controlled by a suitable throttle-valve T, which is operated by means

of the lever L or in other suitable manner, and said motive-fluid passage a of the handle connects with the motive-fluid passage b, having the port b' delivering into the cylinder B. 55

The handle A and throttle-valve T may be of an approved construction, excepting that in order to secure the handle to the cylinder in a simple and effective manner I form the handle with a flange 1, which receives the end of the cylinder B, and with an internal collar 2, which takes over the end of the cylinder B and is pinched between the end of the cylinder and the flange of the cap D, 60 which closes the cylinder when said cap is in position. In order to lock the cap D and handle A to the cylinder B, I form a catch-pocket 3 in the handle of the cylinder for the reception of a spring-pressed ratchet-dog 4, 65 which engages a suitable notch in the head of cap D, and said dog is confined in said pocket by an annular screw-plug 5, the free end of the dog being bent at right angles, as at 4^a, and the screw-plug 5 and handle A having a corresponding recess or seat for the reception of the bent end of dog 4 when the dog is in position to lock the parts together. 70

B indicates the hammer-cylinder, provided with a supply-port b' and an exhaust-port b², 75 and in case a shouldered piston is used the bore of the cylinder is contracted between the ports b' and b², as at 6, to receive that portion of the piston having the least diameter.

C indicates a piston of diameters suitable to fit the internal diameters of the cylinder B, said piston having the channel or passage 7 and the ports 8 extending through its walls, which ports 8 are exhaust-ports and may also be supply-ports, according to the position of the piston (or hammer) within the cylinder and accordingly as they register with the supply-port b' or exhaust-port b² of said cylinder. 80 In addition to said ports 8 I provide the piston with one or more supplemental supply or admission ports 9, so arranged therein as to open or register with the supply-port of the cylinder before one-half of the return stroke of the piston has been effected, and such supplemental port or ports may be made directly 85 through the walls of the piston, as shown at 9 in Fig. 1 of the drawings, or may be in the

form of a groove or channel on the periphery of the piston, as indicated at 9^a in Fig. 2 of the drawings, and in either case said supplemental port will not register with the supply-
5 port of the cylinder until the main ports 8 are closed as to the exhaust-port b² of the cylinder, and therefore said supplemental ports 9 (or 9^a) will never act as exhaust-ports.

The supplemental admission-port 9 (or 9^a)
10 should be of such size that it will not admit the motive fluid so rapidly as to arrest the motion of the piston before it has moved as far after said port is opened as it had previously moved under the impulse due to the
15 pressure of the motive fluid at the other end of the piston—as, for instance, in the case of a shouldered piston such as shown in the drawings the port 9 (or 9^a) should not be so large as to admit sufficient pressure to counterbalance the pressure on the shoulder of the piston and arrest its movement before the piston-port 8 has registered with the inlet-port b' of the cylinder on the return stroke of the piston, and, further, the relative proportion
20 of the supplemental supply or admission port of the piston to the exhaust-port of the piston in order to obtain the best results should not exceed the proportions of one (1) to four (4.)

The construction being substantially such
30 as hereinbefore pointed out, the operation of the machine will be as follows: The piston C being in the position shown in the drawings and the throttle T having been opened to admit the motive fluid to the cylinder, the motive fluid entering through port b' will act upon the shoulder of the piston (or upon the corresponding piston-head) to cause the return stroke of the piston, and when the return movement of the piston has closed the ports
35 8 of the piston with relation to exhaust-port b² of the cylinder the supplemental admission-port 9 (or 9^a, Fig. 2) will have opened to the supply-port b' of the cylinder, whereupon fluid-pressure (dependent on the size of port
40 9 or 9^a) will be gradually admitted to the opposite end of the piston, the piston still continuing its return movement, until sufficient pressure has been admitted through port 9 to arrest the backward movement of the piston,
45 which will then be reversed and make its forward stroke. The small supplemental admission-port 9 (or 9^a) will upon the reverse (or working) stroke of the piston supply the motive-fluid pressure, which will thereafter follow up the piston and somewhat augment the force of the blow. The supplemental supply or admission port 9 (or 9^a) will be closed before the piston-ports 8 open to the exhaust-port b² of the cylinder, so that the
50 supplemental admission-port (9 or 9^a) never acts as an exhaust-port, though the main ports 8 of the piston may, if desired, be arranged to serve alternately as supply and exhaust ports.

65 Among the advantages incident to my invention are simplicity of construction, effi-

ciency in operation, somewhat increased power, and the avoidance of objectionable recoil.

Having thus described my invention, what I claim, and desire to secure by Letters Patent, is—

1. The combination with a cylinder having supply and exhaust ports, of a piston having a supplemental supply-port so arranged with relation to the exhaust port or ports as to maintain a gradual admission of pressure over a large part of the return and forward strokes of the piston, substantially as and for the purposes specified. 70 75

2. In a motive-fluid-operated tool, the combination with a cylinder having supply and exhaust ports, of a shouldered piston having admission and exhaust ports which control the admission and exhaust of the motive fluid 85 to the head of the piston above the shoulder one of said ports being an admission-port only, substantially as and for the purposes specified.

3. In a motive-fluid-operated tool, the combination with a cylinder having supply and exhaust ports, of a shouldered piston having a plurality of ports some of which are supply-ports only and which control the admission of the motive fluid to the head of the piston 95 above the shoulder while others are alternately supply and exhaust ports, substantially as and for the purposes specified. 90

4. In a motive-fluid tool, the combination with a cylinder of a piston having a supplemental supply-port, admission and exhaust ports controlling the admission and release of the motive fluid to and from the cylinder, the supplemental supply-port being of less than one-quarter the cross area of the exhaust 105 ports, substantially as and for the purposes specified. 100

5. In a motive-fluid tool, the combination with a cylinder having supply and exhaust ports, of a piston having a plurality of ports, 110 one of which is a supply-port only, and which does not exceed one-fourth the cross area of the exhaust-ports, substantially as and for the purposes specified.

6. In a motive-fluid-operated tool, the combination with a cylinder, a cap for closing the end thereof, of a spring-dog adapted to engage the screw-cap and provided with a free end which projects at an angle to the dog, an annular screw-plug for confining the spring-dog—said screw-plug having a slot or recess for receiving the bent free end of the dog, substantially as and for the purposes specified. 115 120

7. In a motive-fluid-operated tool, the combination with a cylinder, a cap for closing the end thereof, a handle having a ring or collar clamped between the flange of the screw-cap and the end of the cylinder, of a spring-dog adapted to engage the screw-cap and provided with a free end which projects at an angle to the dog, an annular screw-plug for confining the spring-dog—said screw-plug and handle 125 130

having a slot or recess for receiving the bent free end of the dog, substantially as and for the purposes specified.

8. The combination with a cylinder having supply and exhaust ports, of a piston having a supply-port arranged to gradually admit pressure over a large part of the return and forward strokes of the piston, and an exhaust-port arranged to be opened by the movement

of the piston, substantially as and for the purposes specified.

In testimony whereof I affix my signature, in presence of two witnesses, this 21st day of February, 1900.

CHARLES HARRIS JOHNSON.
